UNITED STATES PATENT OFFICE.

RALPH C. BRONSON, OF CHICAGO, ILLINOIS.

ELECTRIC FUSE.

1,245,863.

Specification of Letters Patent.

Patented Nov. 6, 1917.

Application filed October 23, 1914. Serial No. 868,233.

To all whom it may concern:

Be it known that I, RALPH C. BRONSON, a citizen of the United States, residing at Chicago, in the county of Cook and State 5 of Illinois, have invented a certain new and useful Improvement in Electric Fuses, of which the following is a specification.

This invention relates to electric fuses and has for its object to provide a new and improved device of this description.

One of the objects of my device is to provide an electric fuse particularly adapted for comparatively heavy currents and arranged so that when the fusible strip is blown out 15 the hot metal will not be scattered about and so that the fusible strip can easily, quickly and cheaply be replaced.

When the fuse strip in plugs of this kind is blown there is developed a high pressure on 20 the inside of the casing and where there is an outer rotating part for closing the opening in the casing, this pressure is liable to disrupt or distort the casing, so as to prevent the further use of the device, and one 25 of the objects of my present invention is to provide against the injury due to this pressure.

Electric fuse devices of this kind are used 30 on switchboards and are more or less difficult of access. If, in removing and renewing the fuse metal it is necessary to remove screws or other parts of the device these screws or other parts are liable to be dropped and to thereby be lost, or again picked up 35 with difficulty, thus making such fuse devices commercially impracticable and very difficult to introduce into any extensive use.

One of the objects of my invention is to provide a fuse device where no screws or 40 other parts need be removed when renewing the fusible strip, the device, as it were, being a single structure having no parts which can drop down or be lost during the process of renewing the fusible strip, and, at the same 45 time, provide a good electrical contact at the point where the fuse metal is attached to it so as to insure the proper action of the device, such contact arrangement not being affected by the heat developed when the fuse 50 is blown.

The invention is illustrated in the accompanying drawings, wherein,

Figure 1 is a view showing the invention;

Fig. 2 is a sectional view taken on line

55 2—2 of Fig. 1;

Fig. 3 is a sectional view taken on line 3—3 of Fig. 1;

Fig. 4 is a section taken on line 4—4 of Fig. 1.

Fig. 5 is a view of one of the contact terminals 60 separate from the casing.

Like numerals refer to like parts throughout the several figures.

Referring now to drawings, I have shown an electric fuse of the cartridge type. This 65 device comprises a casing 1 of non-conducting material such as fiber or the like having two metallic end pieces 2. The casing 1, is made up of two parts, an outer cylindrical part 3 and an inner cylindrical part 4. The 70 inner part 4 is stationary and is connected with the end pieces in any desired manner. The outer part 3 is rotatably mounted so that it may be rotated. The inner part 4 is provided with an elongated opening 5 and the outer part 3 is also provided with an elongated opening 6. By turning the outer part 3 the opening 6 may be made to register with the opening 5 so as to permit access 75 to the interior of the casing. When the outer part 3 is rotated so as to move the opening 6 to one side of the opening 5, the casing is then closed.

The ends of the outer cylindrical part 3 project under the metallic end pieces 2 so 80 that said metallic end pieces are engaged by the ends of the outer cylindrical part 3 so as to take the pressure due to the explosion inside the casing when the fuse blows. It will 85 be seen that by this construction the metallic end pieces 2, since they overlap both the inner cylindrical part 4 and the outer cylindrical part 3, grip those parts thereby giving the outer cylindrical part substantially 90 the same strength as the inner part and preventing the pressure due to the blowing of the fuse from bulging or otherwise distorting or injuring the cylindrical parts.

It will be seen if the outer cylindrical part does not extend under the metallic end 100 pieces, the pressure inside the casing will not be greatly resisted by the outer cylindrical parts and the distortion of the parts will, even if it does not disrupt the cylindrical parts, prevent the outer part from 105 being turned on the inner part to close the casing. Projecting through the ends 2 of the casing are the contact terminals 7. The inner ends of these contact terminals are cut away so as to form the narrow neck 8 and 110

the enlarged inner end 9. A bent fastening piece 10 is bent upon the neck 8 so as to project between the enlarged end 9 and the main body of the terminal and the ends 11 thereof bent along the inner surface of the part 4. Screws 12 pass through the caps and the part 4 of the casing and engage the ends of the fastening pieces 10 so as to hold the end pieces 2 and the contact terminals 10 7 in position.

The ends of the outer cylindrical part 3 which projects under the metallic end pieces 2 may be brought into proximity to the screws 12 so that said screws hold said outer 15 cylindrical part against longitudinal movement. (See Fig. 1.)

The inner ends of the contact terminals are provided with the contact screws 13 and the end pieces 14 of the fusible piece 15 are placed under this contact so as to make a clamping electrical contact between the fusible metal strip and the contact terminals 7. The end pieces 2 and the outer part 3 and inner part 4 are slotted opposite these screws 25 as shown in Fig. 1 so as to permit easy access thereto. Then the outer part 3 is rotated so that the openings 5 and 6 register, the slots therein also then register with the slots in the end pieces 2 and the inner pieces 30 4 of the casing.

When the parts are assembled, the fusible metal strip is placed in position by inserting the ends under the contact screws 13 and then tightening said screws so as to get the 35 desired pressure to insure the proper electrical contact. The interior of the casing is then filled with some non-conducting fire-proof material such as powdered asbestos and the casing closed by rotating the outer 40 part 3. When the fuse blows it will be seen that it is entirely inclosed and the explosion is confined within the casing. The end pieces 2 are preferably provided with ventilating openings 16. When the fuse is melted, it is only necessary to rotate the 45 casing 3 so as to bring the opening 6 in position to register with the opening 5. The powdered contents of the casing may then be discharged and the screws 13 loosened by 50 means of a screw-driver and the ends of the fuse metal removed and a new piece of fuse metal inserted. The casing is then again filled with powdered material and the outer part 3 rotated to close the opening. It will 55 therefore be seen that by means of this construction the melted fuse metal can be easily and quickly replaced and the device used over and over again. The contact screws 13 are preferably arranged so that while they 60 can be loosened they cannot be completely removed. This can be done by up-setting the end after the screws have been placed in position. It will be seen that in this fuse 65 there are no removable parts which have to be removed to refill the fuse except the metal

fuse itself, all other parts being fastened together so that they stay together while the new fuse metal is being put in place and hence nothing can be lost in this process to thereby interfere with the proper refilling 70 of the fuse.

I claim:

1. An electric fuse comprising a casing having an outer and inner cylindrical part of non-conducting material, the outer part 75 being rotatably mounted upon the inner part, the two parts provided with openings which are adapted to register when the parts are in a predetermined position so as to give access to the casing, metal end pieces connected with said inner part and overlapping the outer part so that the strength of the outer cylindrical part is utilized to resist the expansion of the inner cylindrical part when the fuse is blown, without interfering with the turning movement of the outer cylindrical part, contact terminals projecting through said metal end pieces, terminal screws connected with the portions of said contact terminals inside 80 said casing, a fusible metal strip having end pieces adapted to be inserted between the heads of said screws and said contact terminals so that by screwing down the screws a good electrical contact can be secured, and 85 slots in said outer and inner cylindrical parts, the slots in the inner cylindrical parts being opposite the heads of said screws and the slots in the outer cylindrical parts registering therewith when the openings in the 90 two cylindrical parts register whereby access to said screws is provided.

2. An electric fuse comprising a casing consisting of an inner cylindrical part of non-conducting material having an opening 105 in the side thereof through which the fuse metal is inserted, two metal end pieces connected therewith one at each end thereof, contact terminals projecting through said 110 end pieces into the interior of the casing 110 and to which the fuse metal is connected, an outer cylindrical part shorter than the inner part and rotatably mounted thereon, said outer part having an opening adapted to register with the opening in the inner cylindrical part when the outer cylindrical part is moved to a predetermined position, said 115 end pieces projecting part way along both the inner and outer cylindrical parts and fixed against rotation with relation to the 120 inner cylindrical part and having a rotatable engagement with the outer cylindrical part so that the strength of the outer cylindrical part is utilized to resist the expansion of the inner cylindrical part when the fuse 125 is blown, without interfering with the turning movement of the outer cylindrical part whereby bulging of the inner cylindrical part so as to interfere with the rotation of the outer cylindrical part is prevented. 130

3. An electric fuse comprising a casing having an outer and inner cylindrical part of non-conducting material, the outer part being rotatably mounted upon the inner part, the two parts provided with openings which are adapted to register when the parts are in a predetermined position so as to give access to the fuse, metal end pieces projecting over the ends of both of said outer and inner cylindrical parts, so as to utilize the strength of the end pieces and the outer cylindrical part in resisting the expansion of the inner cylindrical part due to the pressure produced when the fuse is blown, without interfering with the turning movement of the outer cylindrical part thus preventing the binding of the outer cylindrical part, contact terminals connected with said metallic end pieces and means for removably fastening a fusible metal strip to said contact terminals.

4. An electric fuse comprising a casing having an outer cylindrical part and an inner cylindrical part, both made of non-conducting material, the outer part being rotatably mounted upon the inner part, a removable fuse contained in the inner cylindrical part, the two cylindrical parts having openings adapted to register when they are moved relatively to a pre-determined position so as to give access to said inner cylindrical part, hollow end pieces into which the ends of said inner cylindrical part project, screws passing through said end pieces and projecting into said inner cylindrical part so as to fasten them together, said outer cylindrical part being shorter

than the inner cylindrical part and having its ends in proximity to said screws so that they limit its longitudinal movement, portions of said hollow end pieces projecting over the ends of said outer cylindrical part so as to permit it to rotate but hold it against outward distortion when the fuse is blown.

5. An electric fuse comprising a casing consisting of an inner cylindrical part of non-conducting material having an opening in the side thereof through which the fuse metal is inserted, two metal end pieces having overlapping portions projecting part way along the inner cylindrical part, a part of the overlapping portion of each end piece engaging the inner cylindrical part, there being a space between the inner cylindrical part and the remainder of the overlapping portion of each end piece, an outer cylindrical part of non-conducting material rotatably mounted upon the inner cylindrical part and having reduced end portions which project into the spaces between the end pieces and the inner cylindrical part, said outer cylindrical part having an opening adapted to register with the opening in the inner cylindrical part when the outer cylindrical part is moved to a predetermined position.

In testimony whereof, I affix my signature in the presence of two witnesses this 3rd day of October 1914.

RALPH C. BRONSON.
